UNITED STATES PATENT OFFICE.

JOHN D. LORD, OF WINTHROP, MASSACHUSETTS.

LIQUID-FUEL BURNER.

1,395,846.

Specification of Letters Patent. Patented Nov. 1, 1921.

Application filed September 16, 1919. Serial No. 324,107.

To all whom it may concern:

Be it known that I, JOHN D. LORD, a citizen of the United States, and resident of Winthrop, in the county of Suffolk and

5 State of Massachusetts, have invented certain new and useful Improvements in Liquid-Fuel Burners; and I do hereby declare that the following is a full, clear, and exact description thereof.

10 My invention relates to new and useful improvements in liquid fuel burners of that general type including a mixing burner head arranged to discharge into a combustion chamber which has associated therewith a 15 generator for supplying pressure vapor to the burner head to produce proper discharge of the fuel liquid therethrough.

It is in general the object of my invention to improve the combustion efficiency and the 20 reliability of operation of burners of this character, and it is more particularly my object to insure such treatment of the fuel liquid as to insure complete consumption, particularly by breaking up the chemical 25 composition of the fuel liquid incidental to its discharge from the burner head whereby the fuel liquid will combine with the pressure vapor to form a water-gas combination.

A further object resides in the provision 30 of an arrangement which further insures complete combustion by the maintenance of a temperature in the combustion chamber which is in excess of the igniting temperature of the fuel liquid, and I compass this 35 object by providing a combustion chamber having such restricted dimensions to maintain this temperature in the operation of the burner.

40 A more detailed object resides in the provision of a burner structure having the afore recited characteristics which may be readily adjusted within certain limits of capacity and wherein means is provided to prevent clogging of the burner head passages by scales formed incidental to the generation of steam in the burner apparatus.

45 With the above and other objects and advantages in view, which will be apparent as the description proceeds, my invention resides in the novel features of construction, combination and arrangement of parts as hereinafter described and defined by the appended claims.

In the accompanying drawings:

50 Figure 1 is a longitudinal sectional view through a liquid fuel burner embodying my

invention, the plane of this section with respect to the combustion chamber and generator being indicated by the line 1—1 of Fig. 2.

55 Fig. 2 is an elevational view of the generator chamber, portions thereof being broken away.

Fig. 3 is a side elevational view of the combustion and generator chambers.

60 Referring now more particularly to the drawings, I provide a pressure vapor generating chamber formed by an annular casing 5, the cross sectional area of the chamber being elongated in the plane of the annulus, 70 and being taperingly reduced in width toward the inner periphery of the annulus to afford substantially a pear shaped cross section. This generator casing also forms the front wall of the combustion chamber A and 75 the cylindrical fire brick casing 6 of the combustion chamber abuts one side of the casing A, the combustion chamber being partially closed at its rear by a rearwardly inclined partition wall 7 extending from one 80 side of the casing 6 and terminating adjacent the other side of the casing 6, the combustion chamber A thus having a restricted inlet defined by the inner periphery of the casing 5, and having a still more restricted 85 outlet defined by the free edge of the partition wall 7 and by the opposed side wall portion of the opposed chamber casing 6, the casing 6 being continued a slight distance past the partition 7 and taperingly reduced 90 to form a discharge mouth for the heat carrying combustion gases, the casing 6 being adapted to discharge into a furnace or other space to be heated, and the process of combustion may be carried on rearwardly of the 95 partition wall 7, although it is primarily noted that sufficient combustion takes place in the combustion chamber A to maintain the atmosphere and walls of said chamber at a degree of heat in excess of the igniting 100 or combining point of the fuel liquid discharged thereinto. The casings 6 and 7 are connected together by a pair of semi-circular clamping band sections 8 fitting against the intermediate portion of the casing 6 and 105 having their end portions outturned to provide ears for the reception of the clamping bolts, a pair of upper and lower hook members 10 and 11 being mounted on these bolts and being adapted to engage about the outer 110 periphery of the generator casing 5. The lower hook member is extended past its bolt

9 for engagement with the casing 6, while the other hook member terminates at its respective bolt 9 and is thus freely pivotal whereby it may be swung to engage or disengage the casing 5 and thus provide for readily attaching and detaching the casing 6.

My improved burner head comprises an outer casing 12 having a longitudinal bore 10 therethrough and having an enlargement at one side wherein is provided a longitudinal oil passage 13, said bore and passage being open at the inner end of the casing block. A sleeve 14 is disposed in the main bore of 15 the casing block 12 and has threaded connection with the inner end portion of the block, the major portion of the block being counterbored to form a vapor chamber 15 which is closed at the outer end of the block 20 by a sleeve 16 fitting about the tube 14 and threaded in said counterbore, this sleeve being provided with a suitable packing gland. To provide an adjustable mixing and vaporizing passage for the burner head, a block 25 18 is fitted against the inner end of the casing block 12, and is provided with a bore in which is disposed a passage sleeve 19, said sleeve being provided with an enlargement at its outer end disposed in a countersink of 30 the bore of the block, and being retained in place by a plate 20 fitted against the outer end of the block and sleeve enlargement, said plate being in turn engaged by the in-turned flange portion 21 of a sleeve 22 disposed about the block and plate and threaded on the inner end portion of the casing block 12. The inner portion of the block 18 is recessed to form a small oil chamber communicating with the passage- 35 way 13 and with the mixing sleeve 19. The inner end of said sleeve 19 is beveled on an angle of approximately 45° and forms a valve seat for the correspondingly beveled end of the tube 14, said end of the tube 14 40 being reduced in bore to form a nozzle passage slightly smaller in diameter than the passage of the mixing sleeve 19. Pressure vapor is supplied to the chamber 15 of the casing block by a pipe line 23 having one 45 end threaded in the casing block and having its other end threaded in the upper portion of the outer periphery of the generator casing 5, said pipe line incidentally serving to support the burner head adjacent the generator casing and in axial alignment therewith. The intermediate portion of the tube 14 is provided with a series of apertures whereby it forms substantially a screen for vapor to pass into the interior of the tube, 55 the apertures being, however, no greater in size than the nozzle passage of the tube. The outer end of the tube 14 is closed by a screw plug 24 threaded therein.

Water is supplied to the lower portion 60 of the generator casing through a pipe line

25 in which is disposed a control valve 26, the handle portion 27 of said valve being provided with an abutment screw 28 whereby by the opening movement of said valve may be accurately determined since the amount 70 of water admitted to the generator chamber plays a material part in the operation of the burner.

Describing now the operation of my improved burner apparatus and assuming normal operating conditions to exist, a temperature is maintained in the combustion chamber A which may range from 1800° F., which insures combining of the fuel vapor to a temperature of approximately 3000° F. 80 This generator may incidentally be formed of a bronze having a proportion one part tin to 32 parts of copper whereby to meet the severe condition imposed. Water, upon entering the generator chamber is thus instantly converted into steam and this steam in passing about the generator to the burner head pipe line 23, is changed to highly super-heated vapor, leaving the generator at a temperature of approximately 1000° F. 90 The disposition of this vapor in the chamber 15 of the burner head heats the casing block 12 and thus raises the temperature of the oil in the supply passageway 13 to a point slightly below its boiling point. The vapor 95 leaves the tube 14 and co-mingles with the oil at a temperature in excess of the disintegration temperature of steam, and probably at about 600°. Thus, in addition to completely atomizing the fuel liquid said fuel liquid is raised above its boiling point and enters into a water-gas combination with the pressure vapor in passing through the mixing sleeve 19, thus positively preventing the occurrence of any carbon deposit as a 100 result of the breaking down of the chemical composition of the fuel material. It is noted that the oil is projected into the jet of pressure vapor in a frusto-conical stream, whereby to procure maximum initial admixture. The discharge from the burner head fires as it passes the center of the generator chamber 5, by reason of the intense heat maintained by the restricted size of the combustion chamber A, sufficient air being 115 drawn in through the combustion chamber with the column of material discharged from the burner head to provide adequate supply of oxygen. The conditions of operation are such within the combustion chamber that the interior thereof is somewhat transparent and blue in color, and when the process of combustion is carried on rearwardly of the combustion chamber A a light blue flame is in evidence, thus indicating 120 burning conditions similar to those of thoroughly carbureted community service gas. 125 By reason of the peculiar shape and constituent material of my generator casing 5, the expansions and contractions thereof in- 130

cidental to the operation of the burner prevents continued formation of scale on the wall of the casing, and such scale as may be formed is churned about in the casing in such manner as to prevent an excess accumulation thereof, the scale being thus ground and carried through the pipe line 23 into the vapor chamber 15 of the burner head, and if such particles of scale would be too large to pass through the screen opening of the tube 14 and through the nozzle end of said tube, such scale would churn about in the chamber 15 until properly reduced, thus preventing clogging of the burner apparatus with scale at any point, and thus providing for the continuous discharge of scale from the apparatus. The mixing and jet passages of the burner head may be cleaned by removing the screw plug 20 26 of the tube 14 and passing a fine wire through the tube.

The capacity of the apparatus may be adjusted within certain limits by providing tubes 14 and mixing sleeves 19 having different sizes of bore, and such tubes and sleeves may be readily substituted in the burner head.

Operation of the burner head is controlled by rotating the tube 14 which forms practically a hollow needle valve to control the flow of oil, and by admitting a greater or lesser amount of water to the generator by means of the valve 25 to thus control the degree of pressure of water vapor.

While I have shown and described a preferred embodiment of my invention, it will be appreciated that various changes and modifications of structure may be employed to meet different conditions of manufacture and use without departing in any manner from the spirit of my invention.

What is claimed is:

1. An oil burner comprising an annular water vapor generating chamber, means for supplying water thereto, a cylindrical combustion chamber at one side of said generating chamber, and a nozzle at the other side of the generating chamber, in communication with said generating chamber and having a fuel inlet port whereby said fuel and water vapor are mixed together, said nozzle being so disposed as to discharge said mixture through the space inclosed by said annular generating chamber into the combustion chamber.

2. A burner apparatus comprising an annular water vapor generating chamber means for supplying water thereto, a cylindrical combustion chamber casing having one end engaged against one side of the generating chamber, a partition extending partly across the rear portion of the combustion chamber casing, a mixing chamber arranged to discharge through the annular generating chamber and having fuel and vapor inlet

ports and a connection between the vapor inlet port and the generator.

3. A burner apparatus comprising an annular water vapor generating chamber, a cylindrical combustion chamber casing having one end engaged against one side of the generating chamber, a partition extending partly across the rear portion of the combustion chamber casing, a mixing chamber arranged to discharge through the annular generating chamber and having fuel and vapor inlet ports and a connection between the vapor in the port and the generator, the combustion chamber defined by said generator, cylindrical casing and partition wall being of such restricted dimensions as to maintain therein upon ignition of fuel liquid, a temperature in excess of the combining temperature of the fuel liquid.

4. A burner apparatus including an annular water vapor generator casing having its inner peripheral portion taperingly reduced to form a substantially pear shaped cross section, a combustion chamber at one side of said generator casing, and a mixing chamber at the other side of the generator casing in communication with said generator casing and having a fuel inlet port and arranged to discharge through the space inclosed by said annular generator casing into said combustion chamber.

5. A burner apparatus comprising an annular water vapor generating casing, a cylindrical combustion chamber casing having one end engaged against the side of the generator casing, means connecting said casings, and a mixing chamber disposed at the other side of the generator casing and in communication with the generator casing, and means for supplying fuel to the mixing chamber, said mixing chamber being arranged to discharge through the space inclosed by the generator casing into said combustion chamber.

6. In a burner apparatus, a burner head casing having one end portion reduced, a sleeve extending through the burner head casing and threaded in the reduced portion thereof, said sleeve being provided with apertures in its intermediate portion and having its bore reduced at its threaded end portion, a pressure vapor inlet port in said casing, means for discharging superheated steam therethrough, a fluid chamber at the reduced end portion of the casing, a mixing passageway extending from said chamber means for supplying oil thereto and a seat for the tube in said fuel chamber about said mixing passageway.

7. In a burner apparatus, a burner head casing block provided with a bore extending therethrough and having one side portion enlarged and provided with a longitudinal fuel inlet passageway, the major portion of said bore being countersunk, a

tube extending through the bore and forming a pressure vapor chamber in conjunction with the major countersunk portion of the bore, said tube being provided with apertures at its intermediate portion, means for supplying vapor to the chamber through said apertures and a mixing passageway extending from the end of the tube and com-

municating therewith and with the fuel inlet passageway.

10

In testimony that I claim the foregoing I have hereunto set my hand at Winthrop, in the county of Suffolk and State of Massachusetts.

JOHN D. LORD.
